US00D872732S

(12) **United States Design Patent** (10) Patent No.: **US D872,732 S**
 Smith et al. (45) Date of Patent: ** Jan. 14, 2020

(54) **DISPLAY SCREEN OR PORTION THEREOF WITH A GRAPHICAL USER INTERFACE**

(71) Applicant: **HULU, LLC**, Santa Monica, CA (US)

(72) Inventors: **Hansen Smith**, Los Angeles, CA (US); **John Couch**, Topanga, CA (US); **Josh Nelson**, Los Angeles, CA (US); **Linda Sum**, Santa Margarita, CA (US)

(73) Assignee: **HULU, LLC**, Santa Monica, CA (US)

(**) Term: **15 Years**

(21) Appl. No.: **29/589,983**

(22) Filed: **Jan. 5, 2017**

(51) LOC (12) Cl. **14-04**

(52) U.S. Cl.

USPC **D14/485**

(57) **CLAIM**

We claim the ornamental design for a display screen or portion thereof with a graphical user interface, substantially as shown and described.

DESCRIPTION

The FIGURE is a front view of a display screen or portion thereof with a graphical user interface showing our new design.

The outermost broken line shows an environment, whereas the remaining broken lines show a display screen and elements of a graphical user interface. None of the broken lines form part of the claimed design.

1 Claim, 1 Drawing Sheet
